A. JAEGERS

BACKPLATE OR SIMILAR ARTICLE

Filed Jan. 31, 1924

Inventor
ALBERT JAEGERS

By his Attorney

John M. Cole

Patented June 10, 1924.

Des. 64,853

UNITED STATES PATENT OFFICE.

ALBERT JAEGERS, OF SUFFERN, NEW YORK, ASSIGNOR TO THE SEGAR STUDIOS INC.,
A CORPORATION OF NEW YORK.

DESIGN FOR BACKPLATE OR SIMILAR ARTICLE.

Application filed January 31, 1924. Serial No. 8,488. Term of patent 7 years.

To all whom it may concern:

Be it known that I, ALBERT JAEGERS, a citizen of the German Republic, and a resident of Suffern, county of Rockland, and State of New York, have invented a new, original, and ornamental Design for a Backplate or Similar Article, of which the following is a specification, reference being had to the accompanying drawing, forming a part hereof.

The drawing shows a front view of the back plate or similar article.

I claim:

The ornamental design for a backplate or similar article substantially as shown.

ALBERT JAEGERS.

Witnesses:

L. SEGAR,
JOHN M. COLE.
